UNITED STATES PATENT OFFICE.

FRANK E. FREDERICKS, OF PORT CLINTON, OHIO, ASSIGNOR TO EDNA M. FREDERICKS,
OF PORT CLINTON, OHIO.

MEANS FOR EFFECTING THE CONTINUOUS OPERATION OF MOVING-PICTURE-PROJECTING APPARATUS.

1,199,536.

Specification of Letters Patent. Patented Sept. 26, 1916.

Application filed August 26, 1912. Serial No. 716,967.

To all whom it may concern:

Be it known that I, FRANK E. FREDERICKS, a citizen of the United States, residing at Port Clinton, in the county of Ottawa and State of Ohio, have invented certain new and useful Improvements in Means for Effecting the Continuous Operation of Moving-Picture-Projecting Apparatus, of which the following is a specification.

10 The primary object of my invention is to effect the continuous, uninterrupted operation of motion picture apparatus.

15 A further object of my invention is to provide improved apparatus of this character which will be simple, durable and reliable in construction, and effective and efficient in operation.

Other objects of my invention will appear hereinafter.

20 My invention is exemplified in the construction, combination and arrangement of parts herein described, and shown in the accompanying drawings which illustrate one embodiment of my invention, and more particularly pointed out in the appended claims.

In the drawings, Figure 1 is a view in side elevation of a structure embodying my invention, this view also illustrating a motion picture projecting apparatus mounted upon 30 the casing. Fig. 1^a is a plan view showing the trend of film on top. Fig. 2 is a view in end or side elevation, taken substantially on the line 2—2 of Fig. 1, looking in the direction of the arrows, the casing or inclosure being shown in section. Fig. 3 is a view on the line 3—3 of Fig. 1, looking in the direction of the arrows. Fig. 4 is a vertical partly sectional view on line 4—4 of Fig. 3. Fig. 5 is an enlarged fragmentary view of 40 one of the reels and associated parts. Fig. 6 is a view similar to Fig. 1, but more diagrammatic in character and is intended to illustrate the reels in the act of changing positions after one reel has received and 45 wound up a quantity of film. Fig. 7 is an enlarged detail view in section on the line 7—7 of Fig. 5, looking upward. Fig. 8 is an enlarged sectional view through one of the reels, but diagrammatic in character to 50 illustrate the method of winding the film

upon the reel. Fig. 9 is a view in elevation of the upper portion of the rear side of the structure, showing the film equalizing or film controlling mechanism. Fig. 10 is a plan view thereof, taken substantially on the line 10—10 of Fig. 9, the casing being in section. And Figs. 11 and 12 are simplified diagrams illustrating the trend of the film at different stages in the operation of the mechanism.

60 In the drawings I have illustrated a structure which I have found well adapted for attaining the objects of my invention, but it will be obvious to one skilled in the art after having obtained an understanding of my 65 invention from the disclosures herein made that my invention may be as well embodied in other structures without departing from the spirit and scope of the invention.

70 In the various types and kinds of moving picture apparatus now on the market and in use it is necessary, after the film has been passed through the projecting apparatus or machine head, to rewind or wind back the film upon its original or another reel before 75 it will be in position or condition for use again in the picture machine. This causes annoying delays and intermissions in the "show," to say nothing of the inconvenience and danger incident to rehandling the film. 80

85 My invention eliminates all of these objections and makes it possible to run the apparatus continuously and uninterruptedly for any length of time without changing or rehandling the film in any manner. In carrying out my invention I find that the most satisfactory results can be obtained by using an endless or continuous film, and in practice I intend that each endless film shall contain whatever number of individual picture 90 shows it is desired to present in one performance, although the number of shows and the length of the film may be whatever is found best suited to conditions.

95 An advantage in the provision of a "multi-show" film, lies in the fact that it is only necessary to change the film once for each change of program, and the complete film may be repeated for as many performances as desired without having to wind 100

- back or rehandle the film in any manner. I have shown the mechanism as contained in an inclosure or casing *a* for the reason that it serves not only as a suitable frame on 5 which to mount several of the parts of the mechanism, but it also serves as a protection against fire and thereby conforms to various municipal ordinances. On the top of this casing *a* I have illustrated diagrammatically 10 a moving picture projecting apparatus *B* which comprises a lantern *C* and a machine head or film moving mechanism *D* in accordance with the well-known practice in moving picture projectors. This portion of 15 the apparatus, however, may be of any suitable or desired type. I have illustrated the film 1 as entering the machine head *D* from the upper side and leaving said head on its under or lower side, the head *D* being provided 20 with mechanism for positively propelling or moving the film progressively in a downward direction past the ray of light at such a speed as may be desirable to properly project the pictures.
- 25 I prefer to mount the moving picture projecting apparatus directly on the casing in such a way as to leave only a small portion of film exposed to accident and fire and if desired, that portion may be also covered.
- 30 In the top of the casing are openings 2 and 3 through which the film leaves and enters the main casing, respectively. The vertical support 103 is provided for a guide roller 104 in a plane different from that of the 35 opening 2, so that as the film leaves the main casing, it will be directed at an angle over the guide roller at the upper end of the vertical support and then enter the projecting apparatus. This arrangement directs the 40 film as it leaves the upper portion of the main casing away from the direct rays of light or heat from the rear of the picture projecting apparatus. The guide roller at the upper end of the said support and the 45 guide roller at the opening 3 are in the same plane which is coincident with the inlet and outlet to the moving picture projecting mechanism. It will, therefore, be seen that the main casing incloses and protects the 50 film on the reels, and the portions of the film extending from the main casing to the projector apparatus is amply protected against both accident, which may tear the film, and against such heat as will tend to burn it.
- 55 For the sake of convenience in taking up and paying out the film and in order that the long length of film may be maintained compact, I prefer to use reels or spools as illustrated at *E* and *E'* in the drawings, 60 upon which the film is wound. While more than two reels might be used, I prefer to employ only two for the sake of efficiency and simplicity. These reels are preferably made identical in construction, so that they 65 may be placed at either end of the double
- armed carrier. In the structure shown in the drawings, one of these reels during a certain period of time acts to receive and wind up the film which leaves the picture projecting apparatus, and the other reel during this period of time serves to pay out film to the machine head. During another period of time, however, these conditions are changed and the first mentioned reel, having previously received a quantity of film, 70 becomes a supply reel while the second mentioned reel, having emptied, becomes the receiving reel. In other words, these two reels periodically interchange and one of them performs the function which the other reel 75 previously performed. In order, therefore, that these reels may be conveniently and easily interchanged I mount them at opposite ends of an arm or frame *F*, centrally pivoted at *F'* to rotate in a vertical plane. 80 Thus it is evident more particularly from Figs. 1 and 6 that the series of reels (which in this case involves two reels) is rotary in character about the pivotal center *F'* of the frame or carriage *F*, and the reels may 85 thereby be bodily shifted to interchange their positions and transfer the film, so to speak, from one reel to the other. The reels themselves are rotatably mounted upon the outer ends of the rotary carriage or frame 90 *F* and in the structure shown they comprise cores *E*² and *E*³, respectively, each core having two parallel circular disks or flanges spaced apart to provide therebetween a deep 95 annular space for accommodating a considerable length of film.
- As shown more particularly in Figs. 1, 6, 7 and 8, the reels have film clamps for gripping the film and holding it on the cores to start the film winding on the reels. It 100 will be seen that each core has a relatively large smooth edged depression or recess 7 in its periphery, which depression receives or accommodates a comparatively large cylindrical dog or clamp 8, the proportions 110 of these parts being such that when the clamp 8 is in the recess the general outline (Fig. 8) 115 conforms substantially to the peripheral arc of the core so that the film will wrap smoothly and evenly on the core. These 120 cylindrical clamps extend through openings in the disks of the reels and are pivoted between two lugs 9 outstanding from the outer face of said disks, and each clamping member is provided with a spring 10 normally 125 tending to swing it about its pivot and set it firmly in the depression 7 of the core. The clamping members are so arranged that they may be swung through the openings in the disks of the reel to clear the winding space 130 of the reel and allow the film to lie across the depression 7, whereupon the clamp may then be swung downwardly by its spring and firmly grip the film in the depression 7, as clearly shown in Figs. 6 and 8. It will 130

be noted, however, that the clamping parts are relatively large and formed in generally smooth curves whereby they will not damage or injure the film when they clamp it upon the cores of the reels. These clamps are adapted to operate automatically to clamp or release the film at the proper times as the case may be, and in this structure I accomplish this automatic operation in a simple manner by means of a track or cam 11 disposed in an arc concentric with the arc described by pivotal centers of the reels and located in the same plane as strips 51, 106 and 93.

In the structure shown the reels are intended to lie in a vertical line one above the other, and the reel which occupies the upper position at any period of time serves as the winding or receiving reel, whereas the lower reel serves as the supply or payout reel. The arc-shaped cam 11 therefore lies substantially over one-half of the circle of rotation which the reels describe and extends from substantially the pivotal points of the reels when they are vertically aligned. This is clearly illustrated in Fig. 6. Each clamp 8 has an upstanding pin 12 near its pivot the roller 12¹ on which engages the lower end 11¹ of the cam 11 in such manner as to swing the clamp out of the depression 7 and release the film. This action occurs just slightly after the lower reel starts upwardly toward the position occupied by the upper reel, and the track 11 holds the clamp open until a short time after the reel reaches the upper position. When the lower reel reaches the upper position, in which it is held pending the winding up of the film, the clamp is still held open by the upper end 11² of the cam track. As soon as the reel starts to rotate on its own axis, however, the clamp pin 12 rides off the end 11² of the cam track and the clamp is operated by the spring 10 to grip the film and hold it on the reel.

It should be understood that the upper end 11² of the cam track is hook shaped as shown in Figs. 1 and 6, because formed on an arc of a radius only slightly larger than the radius of the hook E² or E³ of a reel. The track 11 is on an arc approximately equal to the length of one of the arms of the pivoted carrier F. When the reels interchange positions the track 11 performs its function during the rotation of a carrier F through about 180 degrees. The carrier F is then held in the position shown in Fig. 1 by the pin 27 fitting into the notch at the outer end of the locking arm 25. When the upper reel is filled up to a point where the locking arm 25 is released the reels will begin to move to their new positions, as shown in Fig. 6, the clamp pin 12 will engage the curved lower lip portion 11¹ of the track 11, as shown in Figs. 2 and 5, and

the track 11 will hold the clamping cylinder 8 in releasing position, even after the reels have been interchanged and again locked in position, as shown in Fig. 1. The clamping cylinder 8 is not released until after 70 the upper reel has rotated farther so as to permit the clamping pin 12 to escape from the upper hook portion 11² of the track. It will, therefore, be seen that during the interchange of the reels the clamping pin 12 75 is moved through a large arc defined by the track 11, but after the reels have reached their new positions and the upper reel is rotated the clamping pin 12 is rotated on a smaller radius. This accounts for the 80 hook shaped portion 11² of the track. When the pin 12 runs off the auxiliary track 11² the spring 10 will automatically move the cylinder 8 into its recess 7 in the hub of the reel as shown in Figs. 7 and 8. This 85 will cause the film to be doubled upon itself and wound in parallel relation as indicated in Figs. 1, 6, and 8, and shown also diagrammatically in Figs. 11 and 12.

In order that the clamps may be in proper 90 relative position to clamp and release the film as the case may be, I provide a second track or guide 90 which cooperates with two diametrically opposite roller pins 91 on the core of each reel. Hence when the lower 95 reel starts upwardly the clamp of said reel will be in proper position to be operated by the cam track 11. At the point 92 corresponding to the position of the lower reel the guide track 90 is curved so as not to 100 interfere with the free rotation of the reel on its own axis. This curved portion also, in conjunction with the curved short guide 93, operates to properly direct the pins 91 into relation with the track 90. In this 105 structure the film is released when the clamp is on substantially the lowest side of the lower reel core. When, however, the reel arrives at the upper position the clamp will be properly positioned to grip the film 110 again.

The trend of the film and the method of winding it so that during the operation of the mechanism the film may travel in one direction continuously without interruption, 115 is best illustrated by means of the diagrams Figs. 11 and 12. In these figures the reference characters E and E¹ indicate the cores of the reels. Fig. 11 illustrates the lower reel full of film and the upper reel in the act 120 of commencing the winding of the film. It will be observed that the portion G¹ represents that portion of the film which is just leaving the machine head. The upper reel E has started to rotate on its own axis in 125 order to wind the film thereon. In this point in the operation of the parts the clamp of the upper reel has just left the upper end 11² of the cam track 11 and has clamped the film upon the core. Thus the rotation of the reel 130

4

E in the direction of arrow α will cause the film to double upon itself and wind in parallel relation by taking the portion of the film G¹ from the machine head and the portion G² from the lower reel E¹ which previously wound the film in the same general direction and relation that the upper reel E is now doing it. The lower reel E¹ not only pays out the portion G² of the film to the upper reel, but it also pays out the portion G³ of the film in the direction of the arrow γ to the machine head. As soon as the lower reel becomes empty the clamping member 8 thereof is operated to release the film as shown in Fig. 12 and allows the full reel to be swung downwardly into the position occupied by the now empty lower reel E, and the lower reel is simultaneously rotated upwardly to the position which the lower reel E¹ has just left. As before explained, the releasing of the film from the lower reel E¹ occurs just after the reel starts on its upward journey. As soon as the lower reel E¹ reaches the upper position it occupies the same relation to the film as the upper reel E did in Fig. 11, and the reel E simultaneously reaches the lower position and serves as a supply reel. This cycle of operation may go on indefinitely without interrupting or changing the general progression of the film in the one direction indicated by the arrow γ , this being obvious since the intermittent interchanging of positions by the reels always places the reels in the same winding relation to the film; and the film being endless, will continue to travel in the one direction, hence any number of individual shows which the film contains may be repeated in successive order as many times as desired without stopping the mechanism or manually handling the film in any manner. While it may be possible to manually shift or interchange the reels at the proper intervals, it is manifest that such procedure would be rather inconvenient although practicable, because the reels may be proportioned so as to hold enough film to contain all of the individual shows which are to be given in one performance and it would then be necessary to merely rotate the reels to their interchanged positions for each performance, but the film itself would not have to be rewound upon its original reel as is the case at present. In fact the film itself would not have to be handled in any manner, and the mere interchanging of the reels would occupy no more than a second or two of time. I prefer, however, that the structure be entirely automatic so that the operator, after having once placed a full reel of film in the machine, will not have to handle the mechanism or the film in any manner whatever until a change of program is made, except to drive the machine by hand when the manual method of

operating moving picture apparatus is employed, or to start and stop the motor when the apparatus is power driven.

I will now describe the mechanism by which the intermittent interchanging of the reels may be automatically accomplished.

In the structure shown I prefer to drive only the upper reel directly. The pull of the film by this reel may unwind the lower reel or the lower reel may be unwound by the pull on the film extending to the picture projecting apparatus along the direction γ . For this reason the shaft 15 of each reel is mounted in a bearing in the end of the rotary carriage F, and has a gear wheel 16 on its near end, and as each reel is rotated into the upper position its gear 16 enters into mesh with the driving gear 17, the shaft 18 of which is suitably journaled in bearings formed in the casing or inclosure. The gear 17 is loose on the shaft 18 and is driven through a friction clutch 19 from any suitable source of power. In the structure shown I have connected this clutch by a crossed belt 20 with the manual driving mechanism of the machine head, as shown in Fig. 1, although it is clearly obvious that it may be driven separately by an electric motor or otherwise. The action of the clutch is controlled by equalizing or controlling mechanism, which I will describe later.

During the period when the upper and lower reels are in their winding and paying out positions respectively, they are locked in these positions by a long arm 25. This arm is pivoted in a suitable bracket 26 secured to the inner wall of the casing. It has a slot or opening which drops over a pin 27 on each end of the rotary carriage F. (Figs. 1, 2, 3 and 4.) When the frame is rotated the pin 27 slides along the under surface of the outer end of the arm 25, and as soon as the frame reaches a vertical position the pin enters the hole in said arm and locks the mechanism in position. This locking arm is actuated at intervals to assume releasing position, such as when the lower reel is empty, by a follower 28 having a roller end 29 adapted to ride upon the coil of film on the lower reel and follow the gradually decreasing diameter of said coil as the film is paid out. The other end of the follower arm is pivoted in a bracket 30 (Fig. 3) upon a shaft 31, to which it is rigidly connected. Fastened to this shaft is a cam or eccentric 32, upon the periphery of which rides the lower end of a vertically disposed rod 33. This rod is journaled in suitable brackets 34 and its upper end is attached to the rearward end 35 of the locking arm 25. A spring 36 interposed between the upper fixed bracket 34 and a collar 37 on the vertical rod normally tends to force the rod 33 downwardly and thereby swing the locking arm 25 upwardly to release the rotary car-

riage. The rod 33, however, is held against the action of its spring by a spring-pressed dog 38 loosely pivoted upon the shaft 31 and having its nose 39 engaged in a notch 99 in the vertical rod 33.

- 5 When the rollered end 29 of the follower arm has reached a position corresponding to the lower reel becoming empty a pin 40 on the cam 32 arrives in position to strike the 10 dog 38 and release the vertical rod 33, whereupon the rod is forced down by the spring 36 which operation causes the locking arm to release the rotary carriage. The rod 33 is given room to move downwardly 15 a certain amount because by the time the adjustable projection 40 strikes the dog 38 the lowest part of the cam 32 will have been carried around to a point below the end of the rod 33.
- 20 The point in the movement of the follower arm which corresponds to the empty lower reel is a slot 45 in the core of the reel, (Figs. 1, 2, 5, 6 and 7) into which the end 25 29 of the follower arm drops when the slot is exposed by the unwrapping of the reel from the core. As soon as the rotary carriage is thus released the momentum imparted to the upper end thereof through the driving gears, combined with the greater 30 weight of the full upper reel and the pull on the film in the lower reel from the moving picture projecting apparatus causes the carriage F and the reels to rotate until they have reversed position, wherein they are 35 again locked by the locking arm 25 and pin 27, as before described.

- During the upward travel of the empty lower reel the follower arm 28, which rests upon the core of said reel, is swung upwardly toward an almost vertical position 40 and in thus swinging upwardly it rotates the eccentric 32, which forces the rod 33 upwardly against the action of the spring 36 and allows the spring-pressed dog 38 to snap 45 into the notch 99 in the rod 33, thereby restoring the rod 33 to an operative condition, ready to automatically release the carriage, when the lower reel again becomes empty. The follower arm is restored to a position 50 resting upon the lower full reel by riding off of the core of the upwardly traveling empty reel and dropping upon the film of the full reel, which is now riding in lower position. As the carriage F approaches its 55 vertical position the pin 27 at its outer end lifts the arm 25 against the action of the spring 100 until the pin 27 is directly under the notch in the outer end of the arm 25 when the latter will snap into locking position.

When the upper reel is traveling to its lower position it is desirable to retard the turn by the pull of the film on its own axis during its period of travel so as not to 60 change the relative position of the film and

reel. For this reason I have provided a brake or drag for each reel which preferably frictionally holds the reels from rotating backward any more than is necessary to compensate for the tendency of the film to unwind as the reel travels downwardly. This is very effectively accomplished by simple mechanism, such, for instance, as that shown more particularly in Figs. 1 and 2. Here it will be seen that the carriage has 70 two outstanding studs or projections 55 on opposite sides of the rotary axis of the carriage and each of these studs pivotally supports a brake lever 56. The outer ends 57 of these brake levers carry rods 58, which operate longitudinally in bearings in the carriage F and are actuated by springs 59, which normally tend to swing the other ends 60' of the brake rods into frictional engagement with the inner reel disks and thereby 80 brake the rotation of the reels. It is only necessary to retard the action of the reel which is traveling from upper to lower position, and for this reason I provide an arc-shaped cam 61 on the "empty side" of travel 85 of the reel in the path of the ends of the spring-pressed rods 58. The lower end 62 of this cam is inclined so that the spring-pressed rod 58 of the lower reel brake will ride up on the cam 61 and in this manner 90 the brake will be taken off said lower reel while it is traveling from lower to upper position. This cam, however, does not interfere with the action of the upper reel 95 brake while said reel is traveling to lower 100 position.

I prefer to control the pull or tension on the film automatically by causing the film itself to accomplish this action, this being particularly accurate because of the fact that the film itself regulates its own tension. As before mentioned, the upper reel is driven by the gears 16 and 17 through the medium of a friction clutch, which is operated by 105 equalizing mechanism directly controlled by 110 the increasing diameter of the coil of film in the upper reel. I will now describe this mechanism in detail.

Referring more particularly to Figs. 1, 2, 9 and 10 it will be seen that the shaft 18 115 to which the clutch member 19 is fastened, projects through and beyond its bearing 70 in the casing. It is movable longitudinally in its bearings so as to vary the clutching effect on the clutching face 17¹ of the gear 17, 120 and I prefer to interpose a disk of leather 19¹ or other suitable material between the clutch member 19 and the clutch base 17¹ to render the variable friction more gradual. On the outer end of the shaft 18 is a collar 125 or head 71 which, although rotatable on the shaft, is restricted against outward longitudinal movement thereon. Surrounding this head is a longitudinally movable sleeve 72 to which is connected rigidly an arm 73 extend-

ing in a downward direction therefrom. The head 71 also has arms 76 and 101 both of which operate in a spirally disposed cam slot 77 in the sleeve 72 so that by rotating 5 the arm 76 and head 71 relatively to the sleeve 72 the sleeve will be moved longitudinally on the head 71. This longitudinal movement of the sleeve is resisted by a spiral compression spring 78 interposed between 10 the fixed bearing 70 and the sleeve 72. The shaft 18 will thereby be moved longitudinally and cause the clutch member 19 to frictionally grip the gear member 17¹ in proportion to the varying compression on the 15 spring 78. In the structure shown I control this clutch by the varying diameter of the coil of film in the upper or winding reel. I provide a controller arm 79 having a roller 80 at one end which rides on the 20 coil of film in the upper reel (Fig. 9) and thereby follows the varying diameter thereof. This arm is mounted at its other end 81 upon a rotatable shaft 82 which is journaled on bearing brackets 83 and which 25 projects through to the rear side of the casing. The projecting end carries an arm 84 which is connected at 85 to the link rod 86 which extends to the arm 76 of the head 71. Thus it is manifest that as the reel gradually 30 fills up with film the controller arm 79 gradually rotates the head 71 and by reason of the spring 78 and the cam action between the head 71 and sleeve 72 the clutch will be gradually controlled in proportion to the increasing 35 diameter of the coil of film, and thereby equalize the pull on the film through the picture machine head.

While the reels are shifting position the arm 84 rests against the fixed stop 88 which 40 projects rearwardly from the casing as shown in Fig. 10. Therefore the arm 79 will not fall and it will occupy a proper position to allow the lower reel as it ascends to go under the roller 80 at the free end of 45 the arm 79. As the film is wound on the upper reel the arm 79 is gradually lifted upwardly by the increasing diameter of the roll of film. At the lowest position of the arm 79 the arms 76 and 73 occupy the positions indicated by the dotted lines 76¹ and 73¹, respectively. When the reel is filled to the extent indicated in Fig. 9 the parts will 50 occupy the positions indicated by the full lines and when the reel is nearly filled arms 55 76 and 73 will be in the dotted line position 76² and 73².

As the film winds up on the upper reel the equalizing mechanism causes a firmer grip between the frictional clutch members which 60 decreases the slippage between these members which would otherwise be increased. I prefer to have some slippage between the clutch members even at the starting of the upper reel when brought into position empty. Then 65 whenever there is any slack in the film when first put into the machine, for instance, this slack may be taken up quickly and when a pull is exerted on the film the slipping at the clutch begins. As the film winds up the circumference grows larger and therefore the 70 turning effort, or the torque, must be increased in order to maintain the film taut. By increasing the frictional engagement between the clutch members the torque or turning effort will be increased and therefore 75 the required pull on the film will be maintained.

It should be understood that the film travels through the picture projecting apparatus at substantially uniform speed or at such 80 speed as is determined by the driving mechanism. Both before and after entering the projection apparatus the film is somewhat slack or is subjected to only sufficient pull to prevent it from piling up. In other 85 words the film to and from the picture projecting mechanism should be maintained taut and traveling at approximately the same speed it takes through the projecting mechanism.

If it were attempted to drive the upper reel by a positive connection from the same source of power as drives the picture projecting mechanism the film might be taken up sufficiently to keep the film taut at first 90 but as the diameter grew larger the pull would soon become so great as to break the film. Or if the speed of rotation of the film reel were such as not to wind up the film at first as fast as it is paid out from the 100 picture projecting mechanism, then the film would pile up and not wind up properly. In fact in some cases there might be three hundred feet of film on the floor in an endless tangle.

By means of the friction clutch and my improved equalizer the turning effort may be varied automatically as required to maintain the film properly taut at all times. At the start the smaller amount of frictional 110 connection between the clutch members is such as to permit the reel to be turned sufficiently fast to keep the film taut and wound up as fast as it is paid out from the projecting mechanism. This frictional connection is adjustable initially so that the starting torque on the reel may be sufficient to turn the reel at the proper speed and to produce the proper pull on the film as it comes from the picture projecting mechanism. By 115 referring to Fig. 10 it will be seen that this adjustment may be made by means of the nut 102. By turning this in one direction the head 71 with the sleeve 72 thereon is moved inwardly on the rod 18 and the tension on the spring 78 is increased and this increases the friction between the disks 19 and 17¹ and by moving the nut 102 in the other direction this friction is decreased. Besides this adjustment there may be also 130

another which is made by hooking the outer ends of the links 86 and 74 into various holes in the vertically extending arm 84. This is for adjustment when the reel fills up and the pull is not exactly correct. For instance, if as the reel fills up it is found that the frictional engagement should be increased, that is, that the turning effort or torque should be increased, the lower link 10 74 may be moved into the next upper hole. This will increase the tension in the spring 78 because the lower arm 73 is moved farther to the left. Various other connections may be made as by moving the link 86 up 15 one hole which will move the arm 76 farther to the left. If desired the automatic equalizer may be omitted and the nut 102 operated manually.

Preferably the frictional engagement at 20 the clutch is such that slipping will result due to the pull on the film. As the film winds up the film would be pulled faster, because of the larger circumference if a positive driving connection were employed, 25 but when the frictional clutch is used the slippage would increase because of the increasing of the back pull on a larger radius and consequently the pull on the film tends to diminish. Therefore in reality the film 30 tends to be pulled more slowly and it would not be taken up at a sufficient rate of speed unless the turning effort or torque is increased. To increase the torque on the upper reel to drive the increased load due to the 35 increase of weight of the upper film, and the back pull on a larger radius, the frictional engagement of the clutch member is increased automatically and gradually. This results in maintaining a uniform pull on 40 the film after it is paid out from the moving picture projecting apparatus and constantly takes up all slack. This increased torque at the friction clutch, as before explained, is obtained by the equalizing mechanism shown 45 in Figs. 9 and 10. It will be seen that this equalizing mechanism gradually increases the frictional engagement between the clutch members as the film grows larger and more power is required to turn the reel to keep 50 taut the film that is being fed from the picture projecting mechanism.

Sometimes it is desired to run a film faster, for instance when a train is represented as traveling at full speed. But since 55 the film reels are driven from the same driving shaft as the moving picture projecting apparatus the speed of the driving gear 17 (Fig. 2) will be in proportion thereto; that is, the speed of rotation of the gear 17 will 60 be in harmony with the speed of the film moving mechanism of the picture projecting apparatus and therefore whatever the speed of the film through the picture projecting mechanism the speed of the take up 65 mechanism will be in harmony therewith

and the equalizing mechanism will keep a uniform pull on the film to keep the same taut and prevent any slack therein and yet not at any time produce any undue or breaking strain thereon.

When an upper reel entirely or nearly filled with film descends to its lower position the guide pins 91, 91 may be in any position and if one of them is arranged radially with respect to the other it will 70 strike the guiding track 112 a blow and the tendency will be to immediately rotate the reel on its axis until the guiding pins 91, 91 are arranged circumferentially as shown in Fig. 5. In order to relieve the impact or to 75 cushion the blow of the pin 91 against the track 112 I prefer to pivot the latter at 105 as shown in Figs. 5 and 6. In the drawings I have designated the track as 112 and the pivoted bar as 106, the latter being provided 80 with a curved portion 109 joining the lower end 92 of the track 90 at 108. A bracket 110 is provided for supporting a pin 11 which bears against the pivoted member 106. A spring 107 on the pin 111 normally holds the 85 curved portion 109 against the surface 108. When a full reel descends and the pin 91 strikes the track 112 the pivoted bar 106 will yield and the spring 107 will cushion the impact or blow while at the same time 90 the reel will be partially rotated so as to bring the pins 91, 91 into circumferential relation as shown in Fig. 5. The hub of the reel will then be in proper position for rotation and the curved portions 109, 92, and 93 will serve as guides for co-operating with the pins 91, 91 in keeping the reel in proper position. However, the principal function of the pins 91, 91 is to co-operate with the track 90 to hold the clamping pin 12 in its 95 outer radial position. That is, in the position shown in Fig. 5, so that the clamping pin 12 will remain in engagement with the cam track 11 and hold the clamping cylinder 8 out of the recess 7 during the interchanging of the reels. The guiding strips 90, 92, and 93 are all arranged in the same plane. It is intended that the upper reel shall not be released until the roller 29 falls into the slot 45, at which time the pins 91, 91 will be 100 in position to ride along the track 90. But if the upper reel should be released before the pins 91, 91 reach their circumferential relation and the movement of the reel begins sooner than expected the cam guiding 105 surfaces 92 and 93 may be depended upon to properly move the lower reel to such position that the pins 91, 91 will properly co-operate with the track 90. As soon as one of the pins 91 enters the space between the 110 guiding strip 93 and the guide 90 the lower reel is confined and held from further rotation. The guiding strip 93 is of such length as to insure the movement of both pins against the track 90 before either one 115

leaves the track 93. This extension of the track 93 will insure the holding of the pin 12 in engagement with the cam track 11' until both pins 91 engage the track 90, after 5 which the pin 12 will still be held in proper position by the cam track 11.

What I claim is:

1. Moving picture projecting apparatus comprising two reels, means for operating 10 said reels to wind an endless film on one reel and pay it out from the other, and means for changing the positions of said reels periodically to secure a continuous and automatic movement of said endless film.
- 15 2. In an apparatus of the class described, the combination with moving picture projecting mechanism comprising means for moving an endless film always in the same direction, of two reels one for taking up the 20 film as it leaves the projecting apparatus and the other at the same time paying out film to said projecting apparatus, and means entirely automatic for operating said reels to hold the film compactly wound on one or 25 both of the same and means to control the action of said reels to enable the projecting apparatus to be operated continuously and uninterrupted.
- 30 3. In apparatus of the class described, the combination with moving picture projecting apparatus comprising means for moving an endless film continuously and uninterruptedly in a predetermined direction, of means for reeling up the film as it leaves the moving picture projecting apparatus, and means for paying out the film by unreeling the same to said moving picture projecting apparatus, and mechanism for controlling the reeling and unreeling of said film to secure 35 the continuous and uninterrupted operation 40 of said moving picture projecting apparatus, during successive movements of the entire film through said apparatus a plurality of times.
- 45 4. An apparatus of the class described comprising a picture projecting machine, a plurality of film carrying reels, each adapted to rotate on its axis, driving means adapted to drive the film carrying reels alternately to take up film from said projecting device, each film carrying reel being adapted 50 to pay out film when the other film carrying reel is being driven by the driving means, and means for alternately moving the 55 film carrying reels into and out of operative connection with the driving means.
- 60 5. In apparatus of the class described, the combination of an endless picture film, mechanism for propelling said film constantly in one direction, a plurality of reels, 65 means for operating said reels so that one will receive the film from said mechanism and another pay it out to said mechanism, and means for automatically reversing the action of said reels at periodic intervals.
6. In apparatus of the class described, the combination of a plurality of film-holding reels, an endless film extending to the several reels, mechanism for taking the film constantly in one direction from one of said 70 reels and causing it to wind upon another of said reels, and automatic mechanism for intermittently reversing the action of said reels.
7. In film take-up mechanism of the 75 class described, the combination of a plurality of reels, an endless film extending from reel to reel, mechanism for causing one of said reels to wind the film thereon and another of said reels to simultaneously 80 unwind the film at substantially the same rate and for moving the film progressively past a given point in one direction, and automatic mechanism for periodically interchanging said reels and reversing the 85 action thereof.
8. In apparatus of the class described, the combination of an endless film, a plurality of reels one of which is adapted to pay out said film and simultaneously feed 90 the film to another of said reels, mechanism for intermittently causing the film to wind upon said second mentioned reel, and intermittent controlling mechanism adapted to substitute said first mentioned reel 95 when it is empty in the place of said second mentioned reel and cause the film to rewind upon said first mentioned reel.
9. In apparatus of the class described, the combination of a plurality of reels, an 100 endless film, means for doubling portions of the film back upon itself in winding relations to the reels, and a driving means having an operative connection alternately with the reels for winding the film alternately from one to the other of said reels.
10. In apparatus of the class described, the combination of a plurality of reels, an 110 endless film, a driving means, and automatic means adapted to establish operative connection between the driving means and the reels alternately for winding the film alternately from one reel to the other reel.
11. In apparatus of the class described, the combination of a plurality of reels, an 115 endless film, means for doubling portions of the film back upon itself in winding relations to the reels, a driving means adapted to be connected to each of said reels, one at a time, for winding one of said doubled 120 portions on said reel, and means under the control of the film for disconnecting the driving means and said reel and bring the other reel into operative connection with the driving means.
12. An apparatus of the class described, comprising a plurality of reels, an endless film, means for doubling portions of the film back upon itself in winding relations to the reels, a driving means, an operative 130

connection between the driving means and one of the reels for winding one of said doubled portions of the film on said reel, and means under the control of the film for 5 moving said reel out of operative relation with the driving means when a predetermined quantity of film has been wound on said reel and moving another of the reels into operative relation with the driving 10 means to wind another of the doubled portions of the film on the last mentioned reel.

13. In apparatus of the class described, the combination of two reels, an endless film doubled upon itself and wound upon 15 one of said reels, picture machine mechanism through which a continually changing portion of said film is adapted to pass in one direction, a rotary member for carrying said reels and mechanism for automatically operating said rotary member periodically to cause the film to transfer the other of said reels in the same winding relation.

14. An apparatus of the class described comprising two reels, a driving means, an 20 endless film, and automatic means for establishing operative communication between the driving means and the reels alternately for winding the film onto one of the reels while it is being paid out by the 25 other of the reels to effect continuous operation of the film over and over again.

15. An apparatus of the class described comprising a projecting machine, an endless film extending through the projecting 30 machine, a driving means, a plurality of reels, and automatic means for establishing operative connection between the driving means and the reels alternately for winding the film onto one of the reels while it 35 is being paid out by the other of the reels and passed through the projecting machine to effect operation of the film over and over again.

16. In combination, a projecting machine, 40 two film carrying reels, an endless film adapted to pass through the projecting machine and to have portions thereof wound on said reel, a driving means for positively driving the reels, one at a time, to wind up 45 the film as it passes through the projecting machine, and means for connecting the driving means with the reels alternately to wind the film first on one then on the other of the reels in order to pass the film 50 over and over again through the projecting machine.

17. In apparatus of the class described, the combination of a film, and automatic mechanism under the control of the film for successively passing the film in continuous uninterrupted progression past a given point, a plurality of times.

18. In apparatus of the class described, the combination of picture projecting mechanism, an endless film, an automatic take-up

mechanism embodying reels upon which said film is adapted to be wound and unwound, mechanism for controlling the operation of said reels to interchange the reels that are undergoing the winding and unwinding operations, and operating means for the takeup mechanism.

19. In apparatus of the class described, the combination of moving picture projecting mechanism, an endless film adapted to 70 be moved in operative relation to said projecting mechanism in one continuous direction, a reel upon which said film is wound as it leaves said picture projecting mechanism, a second reel from which said film 75 unwinds, means for operating said reels for automatically interchanging the positions of said reels, and means for causing the film to unwind from said first mentioned reel and rewind upon said second mentioned reel.

20. In apparatus of the class described, the combination of moving picture projecting mechanism, an endless film adapted to 80 be moved in operative relation to said projecting mechanism in one continuous direction, a reel upon which said film is wound as it leaves said picture projecting mechanism, a second reel from which said film unwinds, reel operating means mechanism under the control of the moving film for 85 automatically interchanging the positions of the said reels, and means for causing the film to unwind from said first mentioned reel and rewind upon said second mentioned 90 reel.

21. In apparatus of the class described, moving picture projecting apparatus in combination with an endless film adapted to 95 be passed therethrough in one continuous direction, interchangeable take-up reels one of which is adapted to simultaneously receive the film from said projecting mechanism and from a previously wound take-up reel, reel operating means and mechanism under the control of the film for automatically 105 interchanging the filled reel and empty reel.

22. In apparatus of the class described, moving picture mechanism in combination with an endless film adapted to be passed through said mechanism in one continuous direction, a plurality of interchangeable 110 reels each adapted to periodically wind the film thereon as it leaves the projecting mechanism and simultaneously unwind the film from a previously wound reel, and mechanism for interchanging said reels as each reel becomes empty.

23. In apparatus of the class described, moving picture projecting mechanism in combination with an endless film adapted to 115 be moved through said projecting mechanism in one continuous direction, a rotary series of reels each of which is adapted to 120

- periodically receive the film from said projecting mechanism and from a previously wound reel and simultaneously wind the film in parallel relation upon itself, mechanism for carrying a filled reel to the position occupied by a previously filled reel and simultaneously substitute an empty reel, and means under the control of the empty reel for causing the actuation of said positioning mechanism.
24. In combination, a picture projecting machine, an endless film adapted to travel progressively through the projecting machine, a rotary film holding reel, driving means, an operative connection between the driving means and reel, and mechanism connected with said connection for varying the speed of the reel as the size of the roll of the film varies on said reel.
25. In combination, a picture projecting machine, an endless film adapted to travel progressively through the projecting machine, a film holding reel, driving means for rotating the reel, and a connection between the driving means and reel controlled by the size of the roll of film on the reel for driving the reel gradually slower relative to the driving means as the size of the roll of film increases.
26. In apparatus of the class described, the combination of means for progressively moving an endless film, winding mechanism for winding said film into a coil and for paying said film out of said coil, and automatic mechanism under the control of the varying diameter of the coil of film for controlling the speed of rotation of the winding mechanism.
27. In apparatus of the class described, the combination of an endless film adapted to travel progressively in one direction, a plurality of interchangeable reels adapted to intermittently pay out the film progressively, driving means for rotating the reels intermittently to wind up the film, and mechanism actuated by the varying diameters of the coils of film on said reels for governing the power applied to said reels to secure a uniform taking up and paying out of said film.
28. The combination with a moving picture machine, of a plurality of film carrying reels, a rotary carrier for said film carrying reels, means for automatically releasing said rotary carrier and permitting it to rotate through a predetermined angle, means for locking the rotary carrier in the position to which it is rotated, and apparatus for operating said reels to take up the film from said moving picture machine and pay it out thereto.
29. In combination, a picture projecting machine, an endless film adapted to pass through the projecting machine, winding mechanism for taking up the film as it comes from the projecting machine, and means associated with the winding mechanism controlled by the film as the latter is wound for equalizing the tension or pull on the film as it is being taken up after leaving the projecting machine.
30. A picture projecting machine, two film holding reels, an endless film having portions doubled and wound on the reels, driving means, and means for connecting one of the reels with the driving means for first winding portions of the film coming from the projecting machine and the other of the reels onto the first mentioned reel, then for disconnecting the first mentioned reel from the driving means and connecting the second mentioned reel with the driving means for winding portions of the film coming from the projecting machine and first mentioned reel onto the second mentioned reel.
31. In combination, a picture projecting machine, two film holding reels, an endless film, means associated with each reel for engaging a portion of the film and doubling said portion back on itself into winding relation with said reels, a driving means, and an operative connection between the driving means and one of the reels for rotating the latter to wind up substantially equal quantities of film paid out from the projecting machine and the other of the reels.
32. In a device of the class described, the combination with a double-armed carrier pivoted at its middle, of two reels one pivoted to each outer end of said carrier, a gear connected to each of said reels, a driving gear adapted to mesh with one of the reel gears, locking mechanism for holding the double armed carrier in such position that the driving gear is held in mesh with one of the reel gears, and automatic means for releasing said locking mechanism to permit the interchange of the positions of said reels to bring the other reel gear into mesh with the driving gear.
33. In combination, a picture projecting machine, two film carrying reels, an endless film associated with the projecting machine and the reels, driving means for driving the reels, one at a time, to wind the film as it comes from the projecting machine, first on one then on the other of the reels for using the film over and over again without interruption, and means under control of a predetermined quantity of film on one of the reels for moving such reel out of operative connection with the driving means and moving the other reel into operative connection with the driving means.
34. In a device of the class described, the combination with a double-armed carrier pivoted at its middle, of two reels one at each outer end of said carrier, means for

- turning the carrier on its pivotal point, a gear connected to each reel, a driving gear capable of meshing with each of said reel gears, locking mechanism for holding the carrier in a predetermined position, means for holding the carrier, a brake, means for automatically applying said brake to one of said reels as the carrier is turned, and automatic means for releasing said locking mechanism.
35. In a device of the class described, the combination with a double-armed carrier pivoted at its middle, of two reels one at each outer end of said carrier, a gear connected to each reel, a driving gear, locking mechanism for holding the driving gear in mesh with one of said reel gears, automatic releasing mechanism to release said carrier to permit descent of the upper reel, a brake, means for applying said brake to the upper reel as it descends to retard its rotation on its own axis, projections on said reel gears, and a yieldable cam track near the lower limit of movement of the reel gears to be engaged by said projections.
36. In a device of the class described, the combination with a double-armed carrier, of two reels one pivoted to each outer end of said carrier, means on each reel for holding a portion of an endless film in position thereon for winding up, apparatus for rotating said reels to wind the film on one of them, means for automatically interchanging the position of said reels, a cam for releasing the said film-holding-means, and a guide for holding the film-holding-means in releasing position until the reels have been interchanged.
37. In apparatus of the class described, the combination with a double-armed carrier pivoted at its middle, of two reels one pivoted to each outer end of said carrier, a gear connected to each reel to rotate therewith, a film clamp carried by each reel, diametrically disposed pins extending from said reel gears, a driving gear, locking mechanism for holding the carrier in position when the driving gear is in mesh with one of said reel gears, automatic releasing mechanism for effecting an interchange of positions of said reels by the overbalancing weight of the upper filled reel, a cam for releasing the film clamp of the lower reel as it starts to ascend, a brake applied to the upper reel as it descends, a cam for releasing the brake of the lower reel as it ascends, and a guide engaged by said diametrically disposed pins for holding the ascending reel in position when the film clamp is in releasing position until a short time after the gear of said reel meshes with the driving gear, said brake releasing cam also releasing the brake of the descending reel when it reaches the lower limit of its movement where it is free to ro-
- tate at about the time that the driving gear meshes with the gear of the ascending reel and the film clamp on the same is released to clamping position.
38. In a picture machine, winding mechanism comprising two reels, a pivoted reel carrier, means for effecting the rotation of said carrier and means for gradually stopping the carrier when rotated to interchange the position of said reels.
39. A picture machine, a film winding mechanism comprising two rotary reels, a pivoted carrier on which said reels are mounted, guiding devices for said reels and carrier when the latter is rotated to interchange the positions of said reels, a spring pressed buffer mechanism for relieving the impact due to stopping the reel carrier.
40. A picture machine, a film winding mechanism comprising a rotary carrier and rotary reels pivoted to said carrier, guiding pins projecting from the hubs of said reels, a track co-operating with said pins to serve as guiding mechanism, and a spring pressed lever for cushioning the stopping of the carrier.
41. A picture machine, a film winding apparatus comprising a rotary carrier and rotary reels pivoted to the outer ends thereof, a plurality of clamps one associated with the hub of each of said reels, pins projecting from said hubs, a cam track co-acting with said pins to hold the clamps in a predetermined position, and an additional cam track co-acting with said clamp to hold the latter in open position.
42. A picture machine, a film winding apparatus comprising a pivoted carrier and film carrying reels pivoted thereto, film clamping mechanism associated with the hubs of said reels, guiding mechanism for holding one of the reels in a predetermined position while the carrier is being rotated, and a cam track co-acting with said film clamping device to hold the latter in open position while the carrier is being rotated.
43. A picture machine, a film winding apparatus comprising a rotary carrier, and rotary film carrying reels mounted thereon, film clamping mechanism, pins projecting from the hubs of said reels, a guiding track co-operating with said pins to hold the corresponding reel in a predetermined position, an auxiliary guide for directing the said pins on the said guiding track, and an additional track co-acting with said clamping device to hold the latter in open position while said carrier is being rotated.
44. A picture machine, a film winding apparatus comprising a pivoted carrier and film carrying reels mounted thereon, film clamping mechanism associated with the hubs of said reels, apparatus for holding said film clamping mechanism in released

position while said pivoted carrier is being rotated, and an auxiliary track for continuing to hold the film clamping mechanism in released position after the carrier has come to rest and until after one of the reels has been rotated to a predetermined angle.

45. A film winding apparatus comprising a pivoted carrier and film carrying reels pivoted to the outer ends thereof, film clamping devices associated with the hubs of said reels, two laterally projecting pins on each of the hubs of said reels, a substantially semi-circular track co-acting with the pins on the hubs of one of said reels when said pivoted carrier is rotated to interchange the positions of said reels, an additional semi-circular track co-acting with the film clamping devices to hold one of them in open position while said carrier is being rotated, an extension on said last named track for maintaining the film clamping device in released position after the said carrier has come to rest and until the guided reel has been rotated to a predetermined angle.

46. A picture machine, a film winding apparatus comprising a double arm carrier pivoted at its middle, and film carrying reels pivoted at the outer ends of said arms, film clamping devices one associated with each of the hubs of said reels for doubling the film on itself, means for actuating the upper reel for winding the film thereon in parallelism, a plurality of pins, two associated with each of the hubs of said reels, a guiding track co-acting with said pins to hold the ascending reel in a predetermined position, an additional track co-acting with the film clamping device of the ascending reel to hold such clamping device in released posi-

tion while the reel is being held in a predetermined position by the said pins engaging said first named guiding track, and an auxiliary track for holding the film clamping device of the ascending reel in released position after the double arm carrier comes to rest and until the upper reel has been rotated to a predetermined angle permitting the clamping device to engage the film laterally and wind it on the reel which has just ascended, while the film on the filled descended reel is paid out.

47. A picture machine, a film winding apparatus comprising a pivoted carrier and film carrying reels pivoted to the outer ends thereof, film clamping devices, one associated with each of said film carrying reels, means for operating said clamping device to closed position, means for winding the film on one of said reels while it is being paid out from the other, means for opening the clamping device of the paying out reel, mechanism for effecting the interchange of position of the reels, locking mechanism for holding the reels in interchanged position, and driving apparatus for operating the empty reel and causing said film clamping device to grip the film, double it upon itself and wind the same in parallelism on said empty reel.

In testimony whereof I have signed my name to this specification, in the presence of two subscribing witnesses, on this 19th day of August, A. D. 1912.

FRANK E. FREDERICKS.
